[57] CLAIM

The ornamental design for a face mask for trying on clothing without smearing make-up, as shown and described.

DESCRIPTION

FIG. 1 is a front elevational view of a face mask for trying on clothing without smearing make-up showing my new design;

FIG. 2 is a right side elevational view;

FIG. 3 is a top plan view;

FIG. 4 is a bottom plan view; and

FIG. 5 is a rear elevational view with the head encircling band removed for clarity of illustration.
